Primary Examiner — Janice Hallmark(74) *Attorney, Agent, or Firm* — McGarry Bair PC(57) **CLAIM**

The ornamental design for a ceiling fan motor housing, as shown and described.

DESCRIPTION

FIG. 1 is a top perspective view of a ceiling fan motor housing showing my new design in the environment of a ceiling fan;

FIG. 2 is a bottom perspective view thereof;

FIG. 3 is a bottom view thereof;

FIG. 4 is a top view thereof; and,

FIG. 5 is a side view thereof.

The broken lines showing a ceiling fan in FIG. 1 illustrate environmental subject matter only and form no part of the claimed design. All other broken lines depict portions of the ceiling fan motor housing that form no part of the claimed design.
